[57] CLAIM

The ornamental design for adjustable engine, transmission, drive train and fuel cell cradle support, as shown and described.

DESCRIPTION

FIG. 1 is a side elevation view showing my new design for a adjustable engine, transmission, drive train and fuel cell cradle support with its opposite side being a mirror image thereof;

FIG. 2 is also a side elevation view of the apparatus in the closed position with its opposite side being a mirror image thereof;

FIG. 3 is a top view thereof;

FIG. 4 is a bottom view thereof;

FIG. 5 is a front view in the open position thereof;

FIG. 6 is a back view in the open position thereof;

FIG. 7 is a front view in the closed position thereof; and,

FIG. 8 is a back view in the closed position thereof; and,

FIG. 9 is a perspective view thereof.
